(57) **CLAIM**

I claim the ornamental design for a panel and support for an exercise device, as shown and described.

DESCRIPTION

FIG. 1 is a front side perspective view of a panel and support for an exercise device;

FIG. 2 is a top view of the panel and support of FIG. 1;

FIG. 3 is a first side view of the panel and support of FIG. 1;

FIG. 4 is a second side view of the panel and support of FIG. 1;

FIG. 5 is a front view of the panel and support of FIG. 1; and,

FIG. 6 is a rear view of the panel and support of FIG. 1.

The ornamental design that is claimed is shown in solid lines in the drawings. The broken (dashed) lines shown in the drawings are included for the purpose of illustrating environmental elements only and form no part of the claimed design.
